Application July 8, 1946, Serial No. 682,045

11 Claims. (Cl. 140—81.5)

1

This invention relates to apparatus for making wire garment hangers and has for an object the provision of apparatus of the character designated which shall be sturdy of design, reliable in operation and effective to form such hangers at an exceptionally fast rate.

My improved machine is of that type in which pre-cut and straightened blanks are fed one at a time to the forming mechanism and includes among other novel features which will become apparent from a reading of this specification, the provision of improved forming and shaping members including means for forming the body of the hanger and holding it on the body forming members while the shank and hook are being formed. Included in the forming means are cam actuated members for accurately positioning the wire blank as the hanger is being formed. All motions for work on a blank are in proper timed relation by reason of the fact that all such motions are derived from a single cam shaft.

Another important feature of my invention resides in a twister head movable at the appropriate time in the cycle of operation into engagement with the ends of the wire blank to twist them into a shank for the hanger, and in which means are provided to stop the machine in event the ends of the wire are out of alignment with the head.

Apparatus embodying features of my invention is illustrated in the accompanying drawings, forming a part of this application, in which

Fig. 1 is a plan view of the apparatus;

Fig. 2 is a front elevational view;

Fig. 2a is a sectional view taken along the line IIa—IIa of Fig. 2;

Fig. 3 is an end view, partly broken away and partly in section;

Fig. 4 is a detail sectional plan view showing the mechanism for forming the body of the hanger;

Fig. 5 is a diagrammatic perspective view of the main cam shaft and showing the forming jaws and anvils for forming the body of the hanger;

Fig. 6 is a sectional view taken along the line VI—VI of Fig. 4;

Fig. 7 is a sectional view taken along the line VII—VII of Fig. 4;

Fig. 8 is a sectional view taken along the line VIII—VIII of Fig. 4;

Fig. 9 is a detail perspective view of one end of the movable forming bar;

Fig. 10 is a fragmentary sectional view taken along the line X—X of Fig. 4;

Fig. 11 is a detail sectional view taken along the line XI—XI of Fig. 10;

2

Fig. 12 is a wiring diagram of the electric circuits controlling the stop mechanism;

Fig. 13 to 16 inclusive are diagrammatic views illustrating the successive movements of the machine in forming a coat hanger;

Fig. 17 is a diagrammatic perspective view showing the means for imparting motion to the rotary chuck or twister;

Fig. 18 is a detail sectional view taken along the line XVIII—XVIII of Fig. 1;

Fig. 19 is a diagrammatic view illustrating the sequence of operation of the machine; and

Fig. 20 is a side view of the hook forming head. Referring now to the drawings for a better

understanding of my invention, my improved machine embodies a frame having vertical members 10 at one end and 11 at the other end. The vertical members are joined by transverse members 12 at the bottom and 13 at the top. Longitudinally extending members 14 and 15 also join the vertical members at the top, the vertical and transverse members thus forming a working bed, or support for the various parts. Mounted on the cross member 12 at one end of the machine is an electric motor 16 which drives a cross shaft 17 through a V belt 18, the shaft extending the length of the machine. A sprocket 19 mounted on the shaft 17 drives a main cam shaft 21 by means of a sprocket chain 22. As will be later seen, all movements in the forming of the hangers are derived from the main cam shaft 21.

At the front of the machine, I provide a feed hopper 23 having sides and ends, and a bottom formed of downwardly sloping plates 24. Pre-cut and pre-straightened wire blanks B are loaded into the hopper 23 and move by gravity rearwardly toward a notch 26 extending downwardly through the top of the frame, and of a width to pass the blanks one at a time. An agitator bar 27 extending longitudinally of the hopper, parallel to the slot 26 and to the rear thereof forms the back of the hopper. The bar 27 is given a slight reciprocatory motion by means of eccentrics 28 mounted on the shaft 17 and connected to the bar 27 by means of connecting rods 29. The bar 27 serves to place the blanks in parallelism with the slot 26 as they roll downwardly in the hopper and insures that the blanks will not hang up in the slot. The blanks pass downwardly through the slot 26 and come to rest, one on top of the other, on a pair of stationary supports 31 and 32 having shoulders 33 and 34 thereon for engaging the blanks. There are also provided resilient supports 36 and 37 for the blanks which are spaced from the stationary supports 31 and 32, as shown in Fig. 2, and each

comprises a hollow sleeve 37 through which a screw 38 extends and which supports a washer 39 by means of a spring 41. A guard 42 extends downwardly at the rear of the blanks on the stationary support to a point slightly below the upper level of the lowest blank.

Disposed directly to the rear of the lowest blanks B resting on the supports 31 and 32 is a stationary forming bar 43 secured to the rear of the frame as by means of bolts 44. The stationary forming bar 43 is located to one side of a point midway between the ends of the blanks. It is provided with rounded ends 46 and 47 for placing a slight rounded bend at the ends of the body of the hanger while it is being formed for the purpose of preventing the downward bowing of the lower or transverse portion of the hanger when it is finally formed.

In order to form the bends just mentioned, and shown particularly in Fig. 4 of the drawing, I mount a movable forming bar 48 in front of the stationary bar 43 and in front of the three lower blanks B. The movable bar 48 is supported from a stationary bar 49 by means of pins, or bolts 51, and 52 which pass through holes in the stationary bar with which they have a sliding fit and are screwed into the movable bar 48. Springs 53 and 54 surround the bolts 51 and 52 at their outer end and bear against the heads of the bolts to bias the movable bar 48 forwardly away from the blanks B. An actuating pin 56 is secured to the movable bar 48 and passes through an opening 57 in the stationary supporting bar 43. The upper rearward corners of the movable forming bar 48 are cut away as shown at 58 and 59 whereby when the bar is moved rearwardly to strike the two lower blanks B, the upper blank engaged by the movable bar is not subjected to a bending action adjacent the rounded ends 46 and 47. Motion is imparted to the movable forming bar 48 by means of a presser member 61 carried by a rock shaft 62 and disposed, when actuated, to strike the striker pin 56. The rock shaft 62, as shown in Fig. 3 of the drawing, is mounted at the front of the frame of the apparatus and is provided with an arm 63 having a roller 64 on the end thereof, in position to be moved by a cam 65 mounted on the main cam shaft 21, the roller 64 being engaged at the beginning of the cycle of operation as hereinafter described.

Disposed in front of the forming bars, at the ends thereof, are a pair of curved oscillating arms 66 and 67 which are mounted in vertical bearings 68 and 69 on the under side of the upper, longitudinally extending frame member 14. See Fig. 2. The curved arms are each provided, on its upper surface, with a shoulder 72, as shown in Fig. 4, which is disposed as the arm is oscillated, to engage the lowest blank B and bend it about the stationary forming bar 43. Motion is imparted to the arms 66 and 67 by means of sprockets 73 and 74 mounted, respectively, on the lower ends of the shafts 66' and 67' of the arms 66 and 67. Sprocket chains 76 and 77 pass respectively around the sprockets 73 and 74 and are connected at their respective rearward ends to springs 79 and 81. The other ends of the chains are connected to the levers 82 and 83 which are pivoted to the frame at 84 and 86 respectively. Rollers 87 and 88 carried by the levers 82 and 83 bear against cams 89 and 91 which impart motion to the levers and sprocket chains 76 and 77 at the appropriate point in the cycle of operation to rotate the curved arms.

As will be seen, particularly in Fig. 8 of the

drawing, each time the curved arms 66 and 67 oscillate, the lowest blank B resting on the shoulders 33 and 34 of the supports 31 and 32 is engaged by the shoulder 72 on each of the arms and is bent around the stationary forming bar 43 to the triangular shape shown in Figs. 4 and 14 to form the body of the hanger. The oscillating arms 66 and 67 and the forming bar 43 are so positioned with respect to the mid position of the blanks B that one end L of the blank, when bent about the forming bar 43, is longer than the other end S. Also, the oscillating arm 67 is caused to lead the arm 66 in the bending movement so that the short end S of the blank overlies the long end L, as more particularly explained hereafter.

Mounted at the rear of the stationary forming bar 43 midway the ends thereof is an anvil 92. The anvil 92 is stationary and is secured to the main frame by any suitable means, not shown. The rear or working face 93 of the anvil 92 slopes forward slightly from its mid position and is provided with a forming and separating lug 94 extending rearwardly therefrom, the upper half of the lug 94 having a vertical face, as shown, and the lower half being provided with a downwardly inclined projection 96 which serves to position the ends L and S of the blank B vertically when they are bent about the forming bar 43 and anvil 92 by the arms 66 and 67.

Mounted on opposite sides of the anvil 92 are a pair of opposed, reciprocating forming jaws 97 and 98. The jaws 97 and 98 are slidably supported in slots 99 and 101 in the main frame into which fit heads 102 and 103 forming a part of the forming jaws. Longitudinally extending rods 104 and 106 are connected to the jaws 97 and 98 at one end and at the other end, respectively, have mounted thereon roller carrying blocks 107 and 108 having, respectively, rollers 109 and 111 mounted on the under sides thereof. The rollers 109 and 111 bear against the sides of cams 112 and 113 mounted on the main cam shaft 21 which are so shaped, as shown in Fig. 5, as to move the jaws 97 and 98 laterally toward the anvil 92 and hold them in that position for the major portion of a revolution of the cam shaft 21. The cams are relieved as shown at 114 and 116 to permit the forming jaws 97 and 98 to move away from the anvil 92 for a short period during each revolution. The jaws 97 and 98 are moved away from the anvil 92 at such times by means of springs 117 and 118 extending longitudinally of the bed of the machine and secured each at one end to one of the forming jaws and each at its other end to suitable brackets 119 and 121 carried by the main frame. See Fig. 1. The inner working faces of the forming jaws 97 and 98 are flat and rearwardly inclined as shown at 122 and 123, particularly in Figs. 4 and 16, to correspond to the working face 93 of the anvil 92. The under side of the jaw 97 around which the long end L of the blank B is drawn in the bending operation is downwardly sloped as shown at 124 so that said long end is passed under the short end S in bending.

When the forming jaws 97 and 98 move into engagement with the lowest blank B, as shown in Fig. 15, the body of the hanger is formed and the ends L and S of the blank are bent by the forming jaws, in cooperation with the forming lug 94 on the anvil 92 to project rearwardly in parallelism. The blank is gripped and held in that position as shown in Figs. 15 and 16, during further operation and until the hanger is completed.

In order to further insure the proper positioning of the blank B with respect to the anvil 92 and forming jaws 97 and 98, I provide a lifting arm 126 which extends diagonally across the bed of the machine beneath the path of the long end L of the blank, when it is being bent about the stationary forming bar 43. The function of this lifting arm is to raise the blank into the path of the forming jaws. The forward end of the lifter arm 126 is secured to a rocker shaft 127 mounted in suitable brackets 128 on the frame, in front of the main cam shaft 21. Carried by the arm 126 is a bracket 129, having a roller 131, mounted thereon. A small cam 132 on the main cam shaft 21 strikes the roller 131 and raises the arm 126 just before the forming jaws 97 and 98 move into position to engage the blank. The outer end of the arm 126 curves downwardly slightly as shown to insure being beneath the long end L of the blank as it is bent around the stationary forming bar.

The ends L and S of the blank are twisted into a shank T, as shown in Fig. 16, by means of a rotary chuck or twister head 133 having a passage 134 therein, elliptical in cross section to receive the ends L and S of the blank B when the head is moved into engagement with said ends. The head 133, or chuck, is mounted in a suitable bearing 136 on an arm 137 which is pivoted to a bracket 138 on the end of the main frame, to swing in a horizontal plane, the pivot point being shown at 139 in Fig. 1. The arm 137 is provided with a lower brace 141 which is connected to the arm 137 at its outer end by means of a vertically extending member 142, mounted to oscillate in the ends of the arm 137 and brace 141, as shown particularly in Fig. 17 of the drawing. A rod 143 secured to the member 142 extends rearwardly alongside the end of the frame and is guided by a bracket 144 secured to the frame and having an opening therein to receive the rod. A roller 146 is mounted on the member 142 on one side thereof and lies in the path of a cam 147 mounted on the outer end of the cam shaft 21. The cam 147 engages the roller 146 at the appropriate point in the cycle of operation to swing the arm 137 horizontally about its pivot 139 so that the ends L and S of the blank B pass into the opening 134 in the twister head. A spring 148 connects at one end to the arm 137 and at the other to the rear of the frame to return the arm 137 when it becomes disengaged from the cam 147. A stop 149 mounted on the rear of the frame is disposed to engage the arm 137 and limit its backward movement, and an adjustable stop 151, mounted on the front of the frame limits the forward movement of the arm 137.

Rotary motion is imparted to the rotary chuck, or twister head 133, by means of a sprocket chain 152 which passes around a sprocket 153 on the rear of the twister head. The chain 152 is connected at one end to a lever 154 pivotally mounted at 156 on the rear of the frame and having its outer end connected to a return spring 157, the latter being connected at its other end to the frame at 158. The other reach of the chain 152 passes over an idler pulley 159 having its shaft 161 carried by the arm 137 and extends downwardly therefrom, at the end of the frame, over a floating sprocket 162 mounted on a bracket 165 carried by a lever 163. The chain then extends upwardly over a stationary idler sprocket 164 mounted on a bracket 164a secured to the end of the frame. It passes thence downwardly about a second floating sprocket 166 mounted on the

bracket 165. The chain thence passes upwardly and is connected at its upper end at 167 to the bracket 164a. The lever 163 is pivotally mounted at 168 to the end of the frame, at the front thereof, beneath a cam 169 mounted on the main cam shaft 21. The cam 169 is so shaped that when the twister head 133 has moved into engagement with the ends of the blank, the lever 163 is depressed, thereby moving its free end downward with the floating sprockets 162 and 166, imparting a multiplied motion to the sprocket 153 about which the chain 152 passes. During the twisting movement, the arm 154 is swung about its pivot 156, against the tension of the spring 157. It will be noted that the cam 169 is provided with a slight protuberance 171, the purpose of which is to relieve the tension on the lever 163 at the end of the twisting movement and to allow the twister head 133 to relax its strain on the shank of the hanger just before the cam 147 is disengaged from the roller 146 to allow the spring 148 to swing the arm 137 rearwardly with the twister head.

Should it occur that the ends L and S of the blank fail to enter the passage 134 in the twister head 133, I provide means for automatically stopping the machine and preventing damage thereto. The automatic stop mechanism is illustrated diagrammatically in Fig. 12 of the drawing. As therein shown, the motor 16 is provided with the usual circuit 172 and is controlled by a switch 173 connected for operation to the core 174 of a solenoid having a winding 176. The winding 176 is connected on one side to one wire of the circuit 172 and on the other side to a conducting plate 177 carried by the twister head 133 and insulated therefrom. This conducting plate is mounted on the front of the twister head 133 and partially surrounds it. The frame of the machine is connected to the ground as shown. Should the ends L or S of the blank fail to enter the passage 134 and strike the conducting plate 177, a circuit is made through the winding 176, the conducting plate 177, through the blank to ground, thereby energizing the winding 176 and opening the switch 173 to stop the driving motor 16. The switch 173 is closed manually to restart the motor 16.

After the shank has been twisted and formed as described, the long end L of the blank is engaged by rollers 178 and 179 on a rotary hook forming head 181, and the end is bent or formed into a hook as shown in Fig. 16 of the drawing. The forming head 181 is mounted in a suitable bearing 182 carried on the front curved end of an arm 183 secured to a shaft 184 at the rear of the machine. The shaft 184 is mounted in bearings 186 and 187 to swing in a vertical plane. A guide arm 188 is secured to the arm 183 and extends forwardly across the machine to terminate between vertical guides 189 mounted on the front of the machine. A spring 191 is connected to the upper end of the guides 189 at one end and at its lower end is connected to the guide arm 188 to bias the arm 183 upwardly. Depending from the outer end of arm 183 and in position to lie alongside the projecting ends of the blank B as the shank T is formed, is a lug 183a which serves to prevent bending of the shank as the hook is being formed.

On the outer end of the shaft 184 is secured a depending arm 192. A link 193 is connected to the lower end of the arm 192 and extends forwardly across the end of the frame, being supported near its forward end by a depending link 194 connected at 196 to the frame. On the forward end of the link 193 is a roller 197 which lies

in the path of a cam 198 mounted on the cam shaft 21. The cam 198 acts to swing the link 193 rearwardly and rock the shaft 184 through the arm 192 to lower the hook forming head 181 into engagement with the long end L of the blank.

Rotary motion is imparted to the hook forming member 181 by means of a sprocket chain 201 which passes about a sprocket 202 on the upper end of the hook forming member and which is secured at one end to a spring 203. The other end of the spring is connected to the shaft 204 of an idler sprocket 206, mounted on the shaft 184 so as to oscillate therewith. The chain 201 passes around the idler sprocket 206 and thence across to the rear corner of the machine and thence downwardly over an idler sprocket 207. The chain is connected at its lower end to a lever 208 which extends across to the front of the machine and is pivotally connected to the frame thereof at 209. It will be noted that the chain 201 is turned at right angles as shown at 211, between the sprockets 207 and 206 in order to pass over said sprockets. Motion is imparted to the lever 208 by means of a roller 213 mounted on a plate 215 carried by the shaft 21 directly above the lever 208. This roller engages the lever during the cycle of operation and moves the rear end thereof downwardly, pulling the end of the chain 201 downwardly and thereby imparting rotary motion to the sprocket 202. This action occurs after the rotary head 181 has been moved downwardly into engagement with the end L of the blank. The lever 208 is provided with a slight protuberance 214 to provide the final limit of rotary motion to the hook former 181 and which permits a slackening off or reverse motion of the hook former at its completion, thereby releasing it from the blank before it is raised out of the way by the action of the spring 191.

After the hanger has been completed as described, the forming jaws 97 and 98 move laterally away from the anvil 92 and the hanger is stripped from the anvil and the forming bar 43. The ejecting mechanism comprises a rocker shaft 216 mounted in suitable bearings 218 on the frame and having two forwardly extending arms 219 and 221 which terminate immediately adjacent the rounded end 46 and 47 of the stationary forming bar 43. Each of the arms 219 and 221 is provided, adjacent the forming bar 43 with a lug 223 the outer surface of which is inclined toward the forming bar 43, as shown in Fig. 10 of the drawing, and which terminates adjacent the forming bar at a point slightly below the upper surface of the lowest blank B. As shown in Fig. 8, the arm 219 when in its uppermost position bears against the under side of the longitudinal frame member 14 where it extends rearwardly from the hopper 23. The lug 223 performs an important function in the forming of the body of the hanger. As shown in Fig. 10, it will be seen that when the lowest blank B is bent about the stationary forming bar 43 by the arms 66 and 67, the inclined surface 223 causes the front of the hanger, or transverse bar section thereof, to be moved to the lowest position on the forming bar 43. At the same time, as already described, the ends of the blank are being raised by the inclined lug 96 on the anvil 92 and by the lifting arm 126. The blank is thus properly positioned with respect to the anvil, the forming jaws, the twisting mechanism.

Referring to Fig. 18, the shaft 216 has mounted

thereon an arm 224 carrying a roller 226 which rides on the cam 213 for actuating the forming jaw 98. A projection 227 on the cam 213 strikes the roller 226 at each revolution of the cam, thereby rocking the shaft 216 and forcing the arms 219 and 221 downwardly to eject the finished hanger. A spring 228 is connected to an arm 229 on the shaft 216 and at 231 to the frame to bias the shaft 216 clockwise, as shown at Fig. 18, to hold the roller 226 in engagement with the cam 213.

Mounted immediately beneath the forming bar 43 is a slide 232 which is downwardly inclined except at its forward end where it is upturned as shown at 233. The ejected hangers pass down the slide 232 and are retained on the upturned end 233 until removed.

From the foregoing description, the operation of my improved apparatus will be readily understood. Referring particularly to Figs. 13 to 16 and 19, pre-cut and pre-straightened blanks B are placed within the hopper 23 and move by gravity down the inclined bottom pieces 24 to the rear of the hopper. There they are engaged by the reciprocating agitating bar 27 which maintains them parallel with the slot 26 in the bottom of the hopper, through which they pass in single file to rest on the shoulders 33 and 34 of the stationary supports 31 and 32. The lowest blank 30 B is engaged by the shoulders 72 on the oscillating arms 66 and 67 and the blank is bent about the stationary forming bar 43 to the position shown in Fig. 4 of the drawing. While being bent about the stationary bar, the moving forming bar 48 is pressed by the arm 46, forcing the lower two blanks against the forming bar 43 to form the curved end bends.

As the arms 66 and 67 bend the blank to the position shown in Fig. 14, the lifting arm 126 raises the long end L of the blank and places it in proper position to be engaged by the forming jaws 97 and 98. The forming jaws 97 and 98 are next moved laterally with respect to the anvil 92 as shown in Fig. 15 of the drawing, and the body of the hanger is formed with the ends L and S of the blank extending rearwardly in parallelism in front of the twister head 133. The twister head is then moved horizontally to engage the ends L and S, the long end L passing entirely through the opening 134. Rotary motion is then imparted to the twister head 133 by the sprocket chain 152 and the shank T is formed as shown in Fig. 16. When the shank has been formed, the hook former head 181 moves downwardly and the long end L of the blank is engaged by the rollers 178 and 179. Rotary motion is imparted to the hook former by means of the sprocket chain 201 and the hook former is rotated sufficiently for the hook to be formed. As the hook forming is completed, the head 181 is relieved slightly by reason of the roller 213 passing over the projection 214 on the lever 208 whereupon the hook former is raised by the spring 191 out of the way of the hanger. The projecting arms 219 and 221 are next moved downwardly so that the heads 223 engage the finished hanger and strip it from the stationary forming bar 43 and the cycle of operation recommences.

It will be seen that all forming motions are derived from the single main cam shaft 21 and are thus always in properly timed relation. I have found in the actual operation of my improved machine that garment hangers may be formed rapidly and economically. The machine is rarely stopped by reason of defects in the machine and

if a defective blank fails to enter the passage 134 in the twister head 133, the machine is stopped by the motor switch 173 being opened by the solenoid 176, before any damage can result to the machine.

From the foregoing, it will be apparent that I have devised an improved garment hanger machine which is sturdy and reliable of operation and capable of rapid and economical manufacture of hangers.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a wire working machine in which pre-cut wire blanks are fed to forming mechanism one at a time, a hopper for the blanks having a sloping bottom with a narrow slot therein at the side nearest the machine and adapted to pass the blanks one at a time, a longitudinally extending agitating bar alongside the hopper adjacent the slot, a resilient support mounted under the hopper in position to receive the blanks, a forming anvil, and swinging arms having bosses thereon to engage the lowest blank on the support and bend it about the forming anvil.

2. In a wire working machine in which pre-cut wire blanks are fed to forming mechanism one at a time, a hopper for the blanks having a sloping bottom with a narrow slot therein at the side nearest the machine and adapted to pass the blanks one at a time, a longitudinally extending agitating bar in the hopper adjacent the slot, a resilient support mounted under the hopper in position to receive the blanks, a forming anvil, a stationary forming bar in front of the anvil and having rounded ends, a movable forming bar disposed in front of the stationary bar and the lowest blanks on the support, means to drive the movable bar against the blanks between it and the stationary bar to shape slight rounded bends in the blank forming the ends of the body of the hanger, and swinging arms having shoulders thereon to engage the lowest blank on the support and bend it about the anvil.

3. Apparatus as defined in claim 2 in which a stationary retaining means extends downwardly at the rear of the blanks on the resilient supports to a point slightly below the upper surface of the lowest blank.

4. In a machine for making wire garment hangers in which pre-cut blanks are fed successively to the machine, a forming anvil, oscillating arms disposed to engage the blanks successively and bend them in triangular form about the anvil with one end longer than the other, forming jaws mounted to reciprocate on opposite sides of the anvil to form the body of the hanger, means to reciprocate the jaws to engage the blanks successively and hold them in engagement with the anvil until the hanger is completed, a forming lug on the rear of the anvil and cooperating with the forming jaws to turn the ends of the blank in outward parallelism, a twister head having a slot therein for engaging the ends of the blank, a swingable arm upon which the twister head is mounted, means to swing the arm into position for the ends of the blank to be engaged after they are turned outward, means to rotate the twister head to form

the shank of the hanger including means to relieve the twister head when the shank is completed, means to swing the arm out of the way when the shank is completed, and a hook former movable into engagement with the long end of the blank to form a hook therein after the shank is formed.

5. In a machine for forming wire garment hangers including a feed hopper having a slot in the bottom thereof through which pre-cut and pre-straightened blanks pass one at a time, the combination of resilient supporting means for the blanks disposed beneath the hopper, a stationary forming bar and an anvil disposed alongside the lowest blanks and to one side of the mid point between the ends thereof, said forming bar having rounded projections on the ends thereof, a pair of curved arms disposed beneath the blanks and having shoulders thereon for engaging the lowest blank, means to swing the curved arms about the stationary forming bar and anvil to form the body of the hanger with the arm engaging the short end of the blank leading, a movable forming bar disposed to cooperate with the stationary bar and form slight rounded bends at the ends of the body of the hanger, means to actuate the movable forming bar to press the blank against the stationary forming bar, forming jaws on opposite sides of the anvil for engaging the blank and pressing it against the anvil to form the body of the hanger, said jaws having lower downwardly inclined surfaces under which the blank is drawn in bending about the anvil, means to move the jaws into engagement with the blank and hold them in engagement therewith until the hanger is formed, a forming lug on the anvil cooperating with the forming jaws for bending the ends of the blank into outward parallelism, means to twist the ends into a shank, means to form a hook on the long end of the blank, and means to eject the hanger after it is formed.

6. In a machine for making wire garment hangers, a forming anvil, oscillating arms for bending wire blanks successively about said forming anvil with one end longer than the other and with the short end overlapping the long end of the blank, reciprocable forming dies disposed on opposite sides of the anvil and movable inward to press a blank against the anvil and form the body of the hanger, a lifter arm extending across beneath the long end of the blank, and means to actuate the lifter arm in advance of the movement of the forming dies and raise the ends of the blank to position it between the forming dies and the anvil.

7. In a machine for making wire garment hangers, a forming anvil, oscillating arms for bending wire blanks successively about said forming anvil with one end longer than the other and with the short end overlapping the long end of the blank, reciprocable forming dies disposed on opposite sides of the anvil and movable inward to press a blank against the anvil and form the body of the hanger, a lifter arm extending across beneath the long end of the blank, means to actuate the lifter arm in advance of the movement of the forming dies and raise the ends of the blank to position it between the forming dies and the anvil, a forming lug on the rear of the anvil disposed to cooperate with the forming jaws to turn the ends of the blank into rearwardly directed parallelism, and a rotary twister head movable into engagement with the ends of the blank to form a shank for the hanger.

8. Apparatus as set forth in claim 7 in which the twister head is mounted on an arm adapted to swing in a horizontal plane with the head in line with the ends of the blank, and in which means are provided to swing the arm into position for the head to engage the ends of the blank and other means are provided to rotate the head a limited distance of rotation after it has engaged the ends of the blank.

9. In a machine for forming metal garment hangers from wire blanks in which the ends of the blanks are caused to enter and be twisted by a rotary chuck, an electrically conductive member adjacent the chuck and insulated therefrom, a frame for the machine connected to the ground and with which the blank is electrically connected during the twisting operation, an electric motor for the machine, circuits for supplying current to the motor and embodying at least one grounded conductor, a switch in series with the motor, and means responsive to establishment of a circuit through the conductive member and the frame to open the switch.

10. In a wire garment hanger forming machine in which the body of the hanger is first formed from a blank of predetermined length and the ends are then twisted into a shank, an electric motor for driving the machine, a circuit for the motor, a twister head having a longitudinal opening therein for receiving the ends of the blank and twisting them, means to move the twister head into engagement with the ends of the blank, a conducting strip partially surrounding the twister head, and means responsive to contact between an end of the blank and the conducting strip for stopping the electric motor.

11. In a wire garment hanger forming machine in which the body of the hanger is first formed

from a blank of predetermined length and the ends are then twisted into a shank, an electric motor for driving the machine, a circuit for the motor including a switch, a conducting plate carried by the twister head and insulated therefrom, a wire included in the motor circuit, an electro-magnetic device for operating the switch connected to said wire and to the conducting plate, the machine being grounded whereby if an end of the blank engages the conducting plate a circuit is completed through said electro-magnetic device, conducting plate and hanger blank to ground and the switch is opened to stop the motor.
